UNITED STATES PATENT OFFICE.

ALGOT J. E. LARSON, LEON C. LE ROY, AND VICTOR GRONBERG, OF JAMESTOWN, NEW YORK, ASSIGNORS TO ART METAL CONSTRUCTION COMPANY, OF JAMESTOWN, NEW YORK.

METAL CABINET.

Application filed August 18, 1921. Serial No. 493,336.

To all whom it may concern:

Be it known that we, ALGOT J. E. LARSON, LEON C. LE ROY, and VICTOR GRONBERG, citizens of the United States, residing at

5 Jamestown, in the county of Chautauqua and State of New York, have invented a new and useful Improvement in Metal Cabinets, of which the following is a specification.

10 This invention relates to metal cabinets or cases and more particularly to metal filing cabinets of the collapsible or "knock-down" type.

The objects of the invention are to provide a desirable knock-down metal cabinet of simple and strong construction and consisting of relatively few parts which may be easily and inexpensively manufactured; and also to provide a knock-down cabinet 20 which can be quickly and easily assembled by an unskilled person with ordinary tools and which, in such assembled form, presents a most rigid and sturdy structure. Further objects are to improve metal cabinets or cases in the other respects herein-25 after described and claimed.

In the accompanying drawings:

Fig. 1 is a front elevation of a filing cabinet embodying the invention.

30 Fig. 2 is a sectional elevation thereof, on an enlarged scale.

Fig. 3 is a horizontal section thereof, on line 3—3, Fig. 2.

Fig. 4 is a sectional elevation of a portion 35 thereof, showing the means for securing the top of the cabinet in place.

Fig. 5 is a horizontal section of a portion thereof, on line 5—5, Fig. 2.

Fig. 6 is a perspective group view of the 40 sides, top, bottom and back and front frame of the cabinet, disassembled.

Fig. 7 is a vertical section thereof, on an enlarged scale, on line 7—7, Fig. 2.

Fig. 8 is a vertical section thereof, on an 45 enlarged scale, on line 8—8, Fig. 2.

The cabinet of this invention comprises, generally stated, two sides A, a front frame member B, a top C, a bottom D, a back E, and drawer suspension or guide members 50 F, which are separable from each other and may be packed in a relatively small space and may be readily assembled. G represents suitable drawers.

The cabinet has a pair of similar but oppositely arranged side walls or members

A. Each side member A is provided with upper and lower inturned flanges 10 and 11, and is provided on its inner side with a vertically disposed retaining strip 12. The retaining strips 12 which may be welded or otherwise suitably secured to or formed on the sides, are provided with front and rear flanges which are spaced inwardly slightly from the sides A and respectively designated as 13 and 14. The front flanges 13 of the retaining strips are provided with a plurality of spaced notches 15. The rear edges of sides A are provided with flanges 16 extending inwardly or towards each other and the front edges are formed with rearwardly opening channels 17. In the construction illustrated, these channels 17 are formed by bending the front edges of sides A inwardly and then rearwardly. 18 designates a pair of shelf supports, one on the inner side of each side A near its base and provided with a flange 19 spaced from the side A. As shown, the shelf supports are formed by bent metal strips welded to the sides and they terminate short of the front and rear edges of the sides.

The upper, inturned flanges 10 of the sides are each provided with a suitable number of spaced apertures 20. As illustrated in the drawings, flanges 10 terminate short of the front and back of the cabinet for a purpose to be hereinafter explained.

The front frame member B preferably comprises a pair of upright, outwardly opening, channel side bars 21 connected by a plurality of drawer division or strike bars 22 and a bottom apron 23. The strike bars and apron 23 are preferably of the inwardly opening channel shapes shown and are welded or otherwise securely attached to the side channels so that the front frame B will be strong and rigid. The side bars 21 are formed with apertures 24 between each pair of strike bars. When the cabinet is assembled, the forward portion of the side bars 21 seat in the channels 17 of the sides, as shown in Fig. 3, so that the front frame B ties the sides A together and holds their front portions rigidly in place.

The top C preferably has downwardly and inwardly bent front, side and back flanges 25, and the front flange carries a depending tongue 26, adapted when the parts are assembled, to engage behind the rearwardly extending front flanges 17 of

the sides A. The side flanges 25 of the top are provided on their under sides with a plurality of lugs 27 which engage in the holes 20 in upper flanges 10 of sides A.

5 The bottom shelf D preferably has front, rear and side depending flanges 28, the side flanges being adapted to fit snugly in the spaces between flanges 19 of the shelf support and the sides A, the rear and side flanges being cut away or notched as at 29 so as to permit of those portions of the bottom fitting over retaining strips 12.

10 The back E is provided with forwardly extending side flanges 30 and also preferably with forwardly extending top and bottom flanges 31 and 32. Bottom flange 32 is notched at its ends as indicated at 33 so as to fit over flange 14 of retaining strip 12.

15 Each of the drawer guides or suspension channels F has a rearwardly extending tongue 34 near its rear end which fits into one of the notches 15 in retaining strip 12 and interlocks with the strip, as best illustrated in Figs. 2 and 5. The front end 20 of each guide F is provided with a downwardly directed tongue 35 which engages in one of the openings 24 in the side channel 21 of the front frame B. The drawer guides are secured in position by means 25 of suitable fastenings such as small screws 36 or the like, which engage threaded holes 37 in front frame channel 21. The interlocking connections between the drawer guides and the channels 21 and strips 12 30 carry the weight of the guides and the drawers thereon and only one small securing screw 36 for each guide is used, simply to prevent the disengagement of the interlocking parts. The drawer guides may 35 be of any usual or suitable construction.

40 Each frame side bar 21 has a threaded hole 38 near the upper end and the sides A have correspondingly positioned holes 39, to permit the insertion of small screws 45 or the like to hold these parts in their interlocked relation. Each of the inwardly extending flanges 16 of the sides is provided near its upper end with a hole 40 and the back E is provided with a pair of correspondingly positioned threaded holes 41 50 adapted to register with the holes 40 and to receive small screws or the like for the similar purpose of securing the back and sides in their interlocked relation. The top C likewise is secured after being interlocked with the sides of the cabinet by small screws or the like 42 inserted in registering holes in the contacting flanges of 55 the top and sides.

60 The cabinet may be stored and shipped in "knock-down" condition and may be easily assembled by placing the sides on the front frame, then forcing the front frame as far forward as possible in the sides so 65 that the forward portions of upright chan-

nels 21 take their positions in the front channels 17 of the sides. The back E is then inserted downwardly between the sides, the side flanges 30 of the back taking under flanges 14 of the retaining strips and the back is shoved downwardly until its lower end rests on the bottom flanges 11 of the sides A. The back is confined between the rear flanges 16 and the strips 12 on the sides, and rigidly ties the two sides together. Bottom shelf D is then placed in position and engaged with shelf supports 18. The drawer suspension channels are then placed in position, as hereinbefore described, and the sides, front frame and back are then secured together, preferably by means of the four small screws, as explained. The top is then placed in position by inserting the lugs on the top plate into the slots in the top flanges of the sides and pushing the top towards the rear of the cabinet until the rear edge of the top is flush with the back of the cabinet, after which the top is secured by means of the small screws as described. Since the sides, back, front frame and top are joined, as explained, by interlocking parts thereon, these members are rigidly connected independently of the securing screws, and only the few small screws mentioned are required to hold the members in proper relation. The top and bottom arranged and connected as explained hold the cabinet in the intended rectangular shape.

66 We claim as our invention:

1. In a knock-down cabinet, the combination of a back, a pair of side wall panels having integral portions forming rearwardly extending upright channels, a front frame comprising spaced upright side bars connected by cross bars, said channels in said panels being unobstructed and said front frame side bars being adapted to be inserted and snugly fit in said channels, spreader bars releasably attached at their rear ends to said side panels, and at their front ends to said front frame to maintain said upright side bars in said channels. 105

2. In a knock-down cabinet, the combination of a back, a pair of side wall panels having integral portions forming rearwardly extending upright channels, a front frame comprising spaced upright side bars connected by cross bars, said channels in said panels being unobstructed and said front frame side bars being adapted to be inserted and snugly fit in said channels, drawer supporting rails having parts adapted to interlock with parts on said side panels and parts on said front frame whereby said uprights on said front frame are retained in said channels. 115

3. In a knock-down cabinet, the combination of a back, a pair of side wall panels detachably connected to said back and main- 120 125

- tained in fixed, spaced relation to each other adjacent said back by interlocking fixed parts on said side panels and back, said side panels having integral front portions forming rearwardly opening, upright channels, a front member comprising spaced upright side bars connected by cross bars, said frame being adapted to be slipped into place between said side panels with its side bars fitting in said rearwardly opening channels, and drawer guide members releasably attached to the rear portions of said panels and to said front frame to retain the side bars of said frame in position in the channels of said side panels.
4. In a knock-down cabinet, the combination of a back, a top, a pair of side wall panels, and a front frame comprising upright side bars connected by cross bars, complete for ready assembly with said side members, said side panels having parts at their rear portions detachably interlocked with the back and having integral front portions forming rearwardly opening upright channels, whereby the front frame may be readily slipped into place between said side panels with its side bars fitting in said rearwardly opening channels, said top having a part for engaging the channel forming portions of said side members, and a part for engaging said back, whereby said side members and back are braced by said top, lugs depending from the side portions of said top, flanges on said side panels having apertures for receiving said lugs, and stops on said flanges for engaging said lugs to position said top relatively to said side panels and back.
5. In a metal cabinet, the combination of a pair of upright side members having rearwardly opening vertical channels at their front portions, a front frame including a pair of spaced upright side bars connected by cross bars, said side bars being seated in the channels of said side members, upright retaining strips secured to the inner sides of said side members and having vertically disposed rearwardly extending flanges spaced from said side members adjacent the back of said cabinet, a back having side flanges engaging between said side members and said rearwardly extending flanges, flanges extending inwardly from said side members in rear of said back and holding the back in engagement with said rearwardly extending flanges, and a top releasably mounted on said sides.

ALGOT J. E. LARSON.
LEON C. LE ROY.
VICTOR GRONBERG.
